UNITED STATES PATENT OFFICE.

MARCUS S. LEVE, OF OAKLAND, AND LEOPOLD B. DE LAITTE, OF SAN FRANCISCO, CALIFORNIA, ASSIGNEES, BY DIRECT AND MESNE ASSIGNMENTS, TO LEONTINE DANDEVILLE, OF SAN FRANCISCO, CALIFORNIA.

MACHINE FOR CARBURETING AIR.

1,395,505.

Specification of Letters Patent.

Patented Nov. 1, 1921.

Application filed August 6, 1918. Serial No. 248,655.

To all whom it may concern:

Be it known that we, MARCUS S. LEVE, a citizen of the United States, residing at Oakland, in the county of Alameda and State 5 of California, and LEOPOLD BENOIT DE LAITTE, a citizen of France, residing in the city and county of San Francisco, State of California, have invented certain new and useful Improvements in Machines for Carbureting Air, of which the following is a 10 specification.

Our invention relates to improvements in machines for charging air with carbonaceous vapors consisting of gasoline fumes, the air 15 so carbureted being used for heating or lighting purposes, and the object of our invention is to produce a machine capable of charging air with hydrocarbon vapors, forming a gaseous mixture of uniform heating 20 value.

Another object of our invention is to so proceed with the vaporization of the gasoline and the incorporation of the fumes with the air, as to vaporize the several different hydrocarbons composing the gasoline liquid 25 in quantities varying with the proportion of their amount contained in the gasoline, thus leaving no volatile residue.

The further object of our invention is to 30 provide means for automatic self adjustment of the device feeding into the machine the liquid hydrocarbons to be vaporized, as to increase or diminish the quantity thus fed, whenever there is a change in proportion of 35 the several ingredients composing the said liquid, in order to obtain carbureted air having uniform heating value.

The construction and manner of operation 40 of our machine will be better understood by reference to the accompanying drawings, which form part of this specification, and in which Figure 1 is a top plan, showing the driving mechanism and the relative position of the several main parts of the machine; Fig. 2 is a similar plan of the machine with 45 the upper portion removed in order to show more clearly the arrangement of the carbureters. Fig. 3 is a front elevation of the machine; Fig. 4 is a detail of the driving 50 mechanism operating the measuring device and the elevating device supplying gasoline to the carbureters; Fig. 5 is a longitudinal

sectional elevation of the machine taken on line 5—5 of Fig. 2; Fig. 6 is a section through the gasoline tank showing the 55 measuring device in position; Fig. 7 is a sectional elevation of the lower portion of the machine taken on line 7—7 of Fig. 1; Fig. 8 is a cross section of the machine taken on line 8—8 of Fig. 1; and Fig. 9 is a side 60 elevation of the chamber 54 showing the elevating device in position.

In the drawings 1 represents a tank filled with water up to the level 2.

A rotary air pump 3 is placed inside the 65 water tank 1.

The rotary pump is formed of the two circular side plates 4 and 5 joined together by a number of curved plates 9. The said circular side plates are provided with central 70 openings 6, and carry the spiders 7, whereby they are securely mounted upon a central shaft 8 held in the bearings 10 and 11.

The curved plates 9 are placed around the central shaft 8 beginning at one end near 75 the periphery of the side plates, and after running for some distance along an arc concentric with the shaft, they divert toward said shaft and terminate at the other end near the center.

The pump is partly submerged in the water of the tank, leaving a portion projecting above the water level.

A narrow cylindrical drum 30 is secured 80 to the side 5 of the pump.

The pump is driven by an electric motor 12 carrying the small pulley 13 connecting by means of the belt 14 with the pulley 15 secured at one end of the shaft 16.

A pinion 17 keyed at the other end of the 90 shaft 16 is made to mesh with the gear 18 mounted upon the counter shaft 19, while a pinion 20 keyed to said counter shaft is arranged to drive the idler gear 21, which is mounted upon a stationary pin 22 and 95 meshes with the gear 23 carried by the central shaft 8 of the pump.

A hood 24 made air tight and open at the bottom is placed on the top of the tank 1 over the pump, the lower portion being immersed in the water forming an air tight 100 seal.

A gas holder or gasometer is placed on top of the hood 24, said gasometer consisting of

a cylindrical tank formed of an outer wall 25 and an inner wall 26, leaving a concentric space 27 between them, which is filled with water. A cylindrical hood 28 open at the 5 bottom is placed over the said cylindrical tank, the open end being sealed by entering the concentric space 27 and submerging in the water.

A U bent tube 31 is secured to the tank 10 1, one of the branches of said tube entering the interior of the cylindrical drum 30, and the other end, extending upward above the level of the water in the tank 1, enters a tube 32 leading to the interior of the gasometer. When the pump is made to rotate 15 in the direction of the arrow, the outer ends of the curved plates 9, projecting above the water level, inclose a volume of air when submerging, and carrying said air below the 20 water level toward the center, discharge it under pressure into the cylindrical drum 30, and thence into the gasometer through the bent tube 31.

The removal of the air from beneath the 25 hood 24 causes the lowering of the air pressure below said hood.

Vaporizing pans or carbureters 33 and 34 are placed in the inside of the tank 1, the carbureter 33 being placed at one side of 30 the rotary pump 3 and the carbureter 34 at the other side.

The carbureters are made of long flat tubes bent in the shape of oblong helices, the several coils sloping very slightly downward, in order to retard the flow of the 35 liquid.

Inlet tubes 35 and 36 for the admission of gasoline are secured at one end to the carbureters near the top, the other end passing 40 through the wall of the tank 1 projects outside; and drain tubes 37 and 38 secured to the carbureters at the bottom pass through the wall of the tank 1, conveying the residue of the unconsumed liquid outside the tank.

A tank 39 containing the gasoline to be 45 vaporized is attached to the side of the tank 1 adjoining the carbureter 33, and a measuring device, adapted to scoop up a measured volume of gasoline, discharging it 50 into a funnel draining into the carbureter 33, is placed inside the tank 39.

The measuring device comprises a scooping cup 40 provided with an opening 41, a measuring cup 42 formed with an opening 55 43, and a tube 44 joining said cups. The tube 44 is secured to a pivoting pin 45, and receives an oscillating motion from a crank 46, carried upon a shaft 47, joining by means of a connecting rod 48 with an arm 49 secured to said pivoting pin.

At each upward stroke of the measuring device the scooping cup 40 brings up a volume of liquid, which passing through the tube 44, fills the measuring cup 42, the 60 surplus overflowing through the opening

43; and in the downward stroke the cup 42 empties its contents through the tube 50 into the funnel 51 which connects with the inlet tube 35 of the carbureter 33.

The gasoline delivered into the carbureter, 70 draining downward along the several coils, spreads out over the entire bottom, presenting a great area of wetted surface exposed to the current of air passing through, and the gasoline vapors given off from over 75 the entire wetted surface diffuse in the air and are carried off into the hood 24, whence they are transferred by the rotary pump into the gasometer.

The surplus of gasoline remaining in the 80 liquid state continues draining toward the bottom, and becomes discharged through the drain tube 37 and the conduit 52 into the well 53 at the bottom of the chamber 54 which is located on the opposite end of the 85 tank 1.

The chamber 54 is secured to the side of the tank 1 adjoining the carbureter 34. It carries a funnel 55 draining into the inlet 90 tube 36.

An elevating device comprising a scooping spoon 56 attached to a tube 57 is secured to a pivoting pin 58, and receives an oscillating swinging motion from a crank 61 secured to the shaft 47 connecting by means 95 of a link 60 with an arm 59 secured to the tube 57.

At each upward stroke of the elevating device the scooping spoon 56 brings up a volume of liquid from the well 53, and raising it above the discharge end 62 of the tube 57, discharges the contents into the funnel 55, which empties through the inlet tube 36 into the carbureter 34.

The gasoline over the entire bottom surface of the carbureter 34 becomes subject to the action of the current of air, and gives off the remaining portion of the volatile matter in fumes, which become diffused with the air; while the rest of the liquid, 100 if any, consisting of heavy hydrocarbons, passes out through the drain tube 38 and is discarded as residue.

The shaft 47, carrying the crank 46 actuating the measuring device and the crank 115 61 actuating the elevating device, receives motion from the idler gear 21 engaging a friction wheel 63, which is secured to a sliding sleeve 64 fitted with a feather 65 to the shaft 47.

The ratio of gearing between said friction wheel 63 and the idler gear 21 may be varied by moving said friction wheel toward the center of the gear, thus diminishing the speed of said wheel or away from the said 110 center, thus increasing the speed.

The air to be carbureted is drawn in by suction through the inlet pipe 66 into the bottom of the carbureter 34, whence it flows in an upward direction, then leaving the 120 130

carbureter 34 at the top passes through the pipe 67 and enters the conduit 68 connecting with the bottom of the carbureter 33, and flowing in an upward direction through 5 said carbureter 33, it becomes discharged through the conduit 69 into the interior of hood 24, where the air pressure is kept below atmospheric by the action of the rotary pump 3.

10 The air within the hood 24, saturated with hydrocarbon vapors while passing through the carbureters 34 and 33, is then conducted by the rotary pump 3 through the tubes 31 and 32 into the gasometer 28, and is thence 15 discharged through the outlet 29, which in practice connects with the gas main (not shown).

When a measured charge of gasolene is introduced at the top of carbureter 33, the 20 most volatile constituents of the liquid covering the wetted surface become vaporized first, while the heavier constituents left in the liquid state keep gradually draining downward along the wetted surface, where, 25 coming in contact with air less saturated, they continue giving off vapors of the more volatile hydrocarbons then remaining, leaving in the liquid state the still heavier constituents, which continue draining along the 30 lower portion of the carbureter covering a large wetted surface.

The liquid covering the bottom of the carbureters 33 and 34 thus varies in composition all along through the entire length of 35 the continuous channel formed by them, being rich in light hydrocarbons at the top of the carbureter 33, where the gasolene is first fed in, becoming gradually poorer all along as vaporization takes place, and near 40 the bottom of the carbureter 34 the liquid remaining consists of heavy hydrocarbons only, which vaporize very slowly.

The flow of air through each of the carbureters, as it may be observed, is from the 45 bottom upward, while the draining of the gasolene is in the opposite direction.

The air entering at the bottom of carbureter 34 begins to act upon the most refractory portion of the gasolene, when it is 50 least saturated and most capable of promoting vaporization, and becoming more and more saturated, as it moves farther upward, it comes in contact with liquid of a gradually increasing volatility and readily vaporizes 55 and incorporates it.

The several hydrocarbons constituting by 60 their mixture the gasolene used, while passing through the continuous conduit of the carbureters, thus arrange themselves automatically in order of their volatility, each constituent covering a wetted surface increasing directly with the proportion of the whole it forms part of, and inversely with its volatility, an arrangement tending to 65 promote the vaporization of those ingredi-

ents which form a very large portion of the liquid, or which by their nature are evaporated with difficulty.

The several volatile hydrocarbons thus become evaporated and incorporated with 70 the air in quantities varying with the proportion of their amount contained in the gasolene, leaving no volatile residue.

When gasolene rich in light hydrocarbons is used, the measured charge of the liquid 75 introduced in the carbureter 33 becomes evaporated and incorporated with the air long before reaching the bottom part of the carbureter 34, the entering air then merely passes through said lower part without absorbing any vapors.

When the composition of the liquid is poorer in light hydrocarbons, the wetted surface covered by the liquid increases, covering the entire bottom of both carbureters; 85 vaporization then takes place through the entire length of the channel of the carbureters, and a portion of the liquid remaining is discharged through the drain tube 38.

For controlling the amount of gasolene 90 incorporated with the air, in order to form a gaseous mixture of uniform heating value, there is provided a thermostat, heated by a jet of carbureted air taken from the gasometer of the machine, and is so connected 95 with the mechanism actuating the measuring devices, as to supply more often a charge of gasolene when the heating value of the mixture falls, and less often when it rises.

The thermostat consists of a spiral 70, 100 formed of two strips of metal 71 and 72, having different coefficients of expansion, brazed together. One end 73 of said spiral is made stationary, by being secured to a post 74, while the other end 75 is operatively 105 connected by means of a connecting rod 76 with the bent lever 77 actuating the sliding sleeve 64 together with the friction wheel 63.

A burning jet 78 supplied with carbureted air taken from the gas supply pipe is 110 placed under the thermostat.

When the heating value of the carbureted air falls below normal, the temperature of the spiral falls, and the several coils contracting actuate the connecting rod 76, moving it in the direction of the arrow, thus causing the friction wheel 63 to move toward the outside of the idler gear.

The relative speed of the shaft 47 to that of the idler gear 21 or of the rotary air 120 pump 3 is thus increased, causing an increase in the amount of gasolene delivered into the carbureters and a rise in the heating value of the carbureted air.

When the heating capacity of the carbureted air rises above normal, the thermostat spiral 70 becomes overheated, and the coils expand, causing the motion of the connecting rod in the direction opposite to that of the arrow. The friction wheel 63, mov- 130

ing toward the center of the idler gear, decreases the speed of the shaft 47, and retarding the delivery of gasolene into the carbureters, causes the lowering of the heating value of the carbureted air.

Having thus described our invention, what we claim as new and desire to secure by Letters Patent is:

1. In a machine of the character described the combination of a vaporizing pan comprising a long conduit provided with a sloping bottom forming the vaporizing surface; an inlet opening for the admission of gasolene, and an outlet opening for the discharge of air, both located at the top of said conduit; an air inlet aperture located at the bottom of said conduit; a device for introducing gasolene through said inlet opening discharging it upon said downwardly sloping vaporizing surface; and an air pump adapted to carry a volume of air through said conduit over said sloping vaporizing surface in an upward direction from said inlet aperture at the bottom to said outlet opening at the top.

2. In a machine of the character described the combination of a vaporizing pan comprising a long conduit provided with a sloping bottom forming the vaporizing surface; an inlet opening for the admission of gasolene and an outlet opening for the discharge of air, both located at the top of said conduit; an inlet aperture located at the bottom of said conduit; an air pump adapted to carry a volume of air through said conduit over said sloping vaporizing surface in an upward direction from said inlet aperture to said outlet opening; and a measuring device for introducing a measured volume of gasolene through said inlet opening discharging it at the top of said sloping vaporizing surface.

3. In a machine of the character described a water tank; a vaporizing pan formed of a plurality of sections placed

within said tank, each section comprising a long conduit provided with a sloping bottom, an inlet opening for the admission of gasolene, and an outlet opening for the discharge of air, both located at the top of each of said sections; an air inlet aperture, and a drain pipe located at the bottom of each section; a pipe connecting the air discharge aperture of one of said sections and the air inlet opening of another section; means for introducing gasolene through the inlet pipe of the said first section; and means for collecting gasolene from the drain pipe of the said first section, delivering it into the inlet pipe of said other section.

4. In an apparatus of the character described, two carbureting devices connected together, a pump for causing a flow of air through said two devices in series, a device for introducing liquid hydrocarbon into the second device adjacent the carbureted mixture outlet, said hydrocarbon being partially vaporized in said second device, a chamber into which the unvaporized hydrocarbon passes, and a device for introducing changes of said unvaporized hydrocarbon into the first carbureting device, the carbureted mixture formed in the first device passing into the second device.

5. In an apparatus of the character described, a closed casing containing liquid, two carbureting devices submerged in said liquid, a pump partially submerged in said liquid for drawing air through said devices in series and agitating said liquid, means for introducing liquid hydrocarbon into the latter device of the series in which a portion of the hydrocarbon is vaporized, and means for introducing the unvaporized hydrocarbon into the first device of the series.
